Primary Examiner — Paula Allen Greene(74) *Attorney, Agent, or Firm* — Mitchell Law PLLC;
Matthew W. Mitchell(57) **CLAIM**

The ornamental design for a elastane cadaver cover, as shown and described.

DESCRIPTION

FIG. 1 is a front perspective view of an elastane cadaver cover showing my new design;

FIG. 2 is rear perspective view thereof;

FIG. 3 is a rear view thereof;

FIG. 4 is a front view thereof;

FIG. 5 is a left-side view thereof;

FIG. 6 is a right-side view thereof; and,

FIG. 7 is a top plan view thereof.

The broken lines depict environment that forms no part of the claimed design.
